UNITED STATES PATENT OFFICE

FRANK P. JOHNSON, OF MARTINDALE, TEXAS

MECHANIC'S TOOL OR CLAMPING LEVER

Application filed February 9, 1929. Serial No. 338,794.

This invention relates to a mechanic's tool and more particularly to a tool for use in laying flooring or ceiling boards, so that all of the grooved or tongued boards forming the 5 flooring or ceiling will fit closely together while in the process of being nailed to a flooring or ceiling joist.

A principal object of this invention is to provide a tool in which the use thereof enables 10 a carpenter to lay flooring or ceiling boards with less difficulty and in a shorter period of time, and without bruising the tongue or grooved sides of such flooring as has been the practice heretofore.

15 It further consists of other novel features of construction, all as will be hereinafter fully set forth.

For the purpose of illustrating the invention, as shown in the accompanying drawings, 20 one form is at present preferred, since the same has been found in practice to give satisfactory and reliable results, although it is to be understood that various instrumentalities of which this invention consists, can be variously arranged and organized and that the 25 invention is not limited to the precise arrangement and organization of these instrumentalities as herein shown and described.

Figure 1 is an isometric view of the tool 30 showing the way in which it is used in holding a flooring board flush against the adjacent flooring board, the jaws of said tool being straddled between the sides of a flooring joist.

35 Figure 2 is a fragmentary isometric view of one of the straddling jaws of the tool with a notched end therein.

Referring now more particularly to the drawings, my invention comprises two curved 40 relatively long handles or levers 10 and 11 which are crossed and pivotally connected by a rivet, bolt or pivot pin 12. The levers 10 and 11 then extend further for a short distance each on the opposite side of the pivot pin 12, each lever taking a right angle turn at 13 and 14 respectively. From here the levers each extend away from each other for a relatively short distance and then again receive a second right angle turn at 15 and 16, 45 and then continue to be spaced apart in a sub-

stantially parallel arrangement from this last right angle turn for another comparatively short distance. Up to this point it will be seen that the portions of the levers thus far described all lie in one and the same 55 plane. At the points 17 and 18 a third right angle bend is given the levers, so that contact arms 19 and 20 will lie in a plane that is approximately at right angles to the plane that the portions of the tool lie in thus previously described. At the points 21 and 22 each of the levers assume a fourth right angle bend so that straddling jaws 23 and 24 are approximately parallel to each other. A final 60 or fifth right angle bend is now given to the 65 tool at the points 25 and 26 from which extends grips 27 and 28 each being notched at 29 and 30, so that a biting contact may be easily had therewith when the tool is used to straddle a floor or ceiling joist J and 70 thereby actuated to move a board or plank K sideways close up against a board or plank L already nailed upon the joist J.

It will be seen that each of the levers of this tool has five distinct right angle turns 75 or bends, not all of which lie in the same plane. The length of the different arms in between the respective right angle turns may be made in accordance with the width of the board and joist that the tool is to be used 80 with.

In order to operate this tool the carpenter 85 opens or spreads apart the levers or handles 10 and 11 so that the clamp will straddle the flooring joist J with the notched ends 29 and 30 gripping into the flooring joist J. The 90 flooring board L is already nailed upon the joist J so that the carpenter is enabled to bring the next flooring board K flush against said flooring board L by merely bearing down 95 on the handle bars 10 and 11 which will cause the contact arms 19 and 20 to abut forcefully against the side of the flooring board K and thereby move the same absolutely flush against the side of the adjacent flooring board L. Furthermore this tool can be manipulated 95 by one hand of the carpenter or mechanic while he uses his other hand to hammer or drive the nails in the board K. It will thus be seen that this tool eliminates the batter. 100

ing up with a hammer, inasmuch that the carpenter is not required to demolish the groove or tongue side of the flooring plank or otherwise spike the flooring plank to secure the 5 results accomplished through the use of this invention.

It will now be apparent that I have devised a novel and useful construction of a mechanic's tool which embodies the features of 10 advantages enumerated as desirable in the statement of the invention and the above description, and while I have, in the present instance, shown and described a preferred embodiment thereof which has been found 15 in practice to give satisfactory and reliable results, it is to be understood that the same is susceptible of modification in various particulars without departing from the spirit or scope of the invention or sacrificing any of 20 its advantages.

Having thus described my invention, what I claim as new and desire to secure by Letters Patent is:—

1. A mechanic's tool comprising a pair of 25 levers pivoted intermediate their ends, said levers serving as handles at one end and their other ends each being bent into a plurality of right angles, some of which right angle bends lie in a horizontal plane, others of which 30 right angle bends lie in a vertical plane, as and for the purpose set forth.

2. A mechanic's tool comprising a pair of levers pivoted intermediate their ends, said 35 levers serving as handles at one end and their other ends as a pair of gripping leverage clamps, said clamps each being bent into a plurality of right angles, some of which right angle bends lie in a horizontal plane, others of which right angle bends lie in a 40 vertical plane, as and for the purpose set forth.

3. A mechanic's tool comprising a pair of levers pivoted intermediate their ends, said 45 levers serving as handles at one end and their other ends each being bent into five right angles, two of which right angle bends lie in the same horizontal plane, another two of which right angle bends lie in the same vertical plane, and another of which right 50 angle bend lies in a horizontal plane parallel to the first mentioned horizontal plane, as and for the purpose set forth.

4. A mechanic's tool comprising a pair of levers pivoted intermediate their ends, said 55 levers serving as handles at one end and their other ends as a pair of gripping leverage clamps, said clamps each being bent into five right angles, two of which right angle bends lie in the same horizontal plane, another two 60 of which right angle bends lie in the same vertical plane, and another of which right angle bend lies in a horizontal plane parallel to the first mentioned horizontal plane, as and for the purpose set forth.

5. A mechanic's clamping tool comprising

a pair of levers pivoted intermediate their ends, one adjacent pair of the ends of said levers being formed into a handle, the other ends of said levers extending in a common plane beyond the pivoted connection, said latter ends being spaced a substantial distance from each other, said spaced ends being bent in a plane substantially at right angles to said common plane, and a pincer formed at the end of each spaced end, whereby 70 said pincer ends may be clamped into the opposite sides of a joist and act as a fulcrum for the spaced ends to press and hold a fresh plank in place on said joist and against the flooring already nailed on said joist while said 75 fresh plank is being nailed between said spaced ends to said joist.

6. A mechanic's clamping tool for clamping and holding a plank against the flooring while in the process of being nailed thereto, 80 said tool comprising a pair of pivoted levers having one pair of ends formed into a handle and the other pair of ends formed into opposing pincers, said pincer ends having adjacent portions substantially spaced from 85 each other, said spaced portions being in a plane substantially at right angles to the plane of said handle end.

In testimony whereof I affix my signature.
